FOLDING BED

Wilfred D. Driver, Thessalon Township, Algoma District, Ontario, Canada

Application March 24, 1951, Serial No. 217,389

7 Claims. (Cl. 5—2)

1

My invention relates to improvements in folding bed structures of the type wherein the folding bed, when in the closed vertical position, is contained within a cabinet which may be arranged against a wall of the room in which the bed is contained, or set within a suitable recess.

The object of the invention is to provide an open faced cabinet having a pair of stationary vertical side members and between which a mattress containing frame is pivotally mounted intermediate of its length, whereby it may be swung from a vertical position between the side members to a horizontal position extending outwardly from the side members and inwardly between the side members.

A further object of the invention is to secure a panel to the underface of the mattress containing frame, the panel forming a closure for the open face of the cabinet when the mattress containing frame is in the vertical position within the cabinet.

Another object of the invention is to insert a counter-balancing spring element between the inner end of the mattress containing frame and the lower inner portion of the cabinet, whereby the spring element counter-balances the weight of the mattress containing frame when it is being swung into the open or closed position; a blanket retaining board being also contained within the cabinet and hingedly secured to the inner end of the mattress containing frame and moveable from one substantially vertical position to another as the mattress containing frame is swung.

A still further object of my invention is to position a piece of furniture in front of the mattress frame panel when the panel is in the vertical position and to provide actuatable means connecting the piece of furniture to the folding bed structure, whereby it may accommodate itself or be accommodated to the downwardly swinging movement of the panel when the mattress containing frame is swung downwardly.

An alternative object of the invention is to permanently attach a piece of furniture simulating a fireplace to the front face of the panel and which will swing downwardly therewith with the downward movement of the mattress containing frame.

With the foregoing and other objects in view, as shall appear, my invention consists of a folding bed structure constructed and arranged—all as hereinafter more particularly described and illustrated in the accompanying drawings in which:

Fig. 1 is a vertical cross-sectional view of the 55

2

folding bed structure to which a swingable piece of furniture simulating a fireplace is attached, and showing the bed in the downwardly swung or open position.

5 Fig. 2 is a fragmentary vertical cross-sectional view taken through the line 2—2, Fig. 1.

Fig. 3 is a front elevational view of the structure as illustrated in Fig. 1, and showing the bed in the closed position within the cabinet.

10 Fig. 4 is a horizontal cross-sectional view through the lower portion of the closed structure, being taken through the line 4—4, Fig. 3.

Fig. 5 is a plan view of the structure arrangement as shown in Fig. 3, the rearward portion of 15 the top face of the cabinet being broken away to disclose the blanket board assembly positioned therebeneath.

Fig. 6 is a vertical cross-sectional view through the closed structure, being taken through the line 6—6, Fig. 5.

20 Fig. 7 is a front elevational view of the lower portion of an alternative form of structure, wherein a piece of furniture simulating a fireplace is attached to the front face of the panel secured to the mattress containing frame, the view illustrating the structure in the closed position.

Fig. 8 is a vertical cross-sectional view through the portion of the structure shown in Fig. 7, being taken through the line 8—8, Fig. 7.

25 Fig. 9 is a front elevational view of the lower portion of the closed structure, showing a folding settee positioned in front of and operatively secured to the front face of the mattress containing frame panel.

30 Fig. 10 is a vertical cross-sectional view through the portion of the structure illustrated in Fig. 9, showing the bed in the open position and the settee in the folded position therebeneath, and

Fig. 11 is a similar view to Fig. 10, showing the mattress containing frame in the closed position within the cabinet and the open settee positioned in front of the vertical panel.

35 Like characters of reference indicate corresponding parts in the different views of the drawings.

40 Referring to all of the drawings, the open faced cabinet comprises a pair of vertical parallel side members 2 having a top piece 3 extending between their upper edges. A back 4 extends between the rear edges of the side members 2, with its lower edge spaced away from the floor upon which the structure rests.

45 The mattress containing frame 5 is of rectangular form and is pivotally mounted upon pins 6 carried upon the inner faces of the side members

2 intermediately of the length of the mattress containing frame. The design of the structure is such that the mattress containing frame, when in the closed vertical position, is contained within the cabinet and when in the horizontal position extends outwardly from the cabinet side members and inwardly between the cabinet side members. A rectangular panel 7 is secured to the underface of the mattress containing frame 5 and is so dimensioned that it forms a closure for the open face of the cabinet when the mattress containing frame is in the vertical position. The mattress containing frame contains a mattress 8 of standard size and construction.

To furnish a counter-balance for the weight of the bed, when being swung, a pair of coiled springs 9 are provided to extend from the rear corners 10 of the cabinet to links or cables 11 which are secured to a swingable arm 12 pivotally attached by a hinge 53 to the inner end of the mattress containing frame 5. An arm supporting bracket 13 is also attached to the inner end of the mattress containing frame 5 and positioned underneath the swingable arm 12 to engage said arm and retain it in the horizontal position when the bed is open, as illustrated in Fig. 1. When the bed is being swung to the closed position within the cabinet, the springs 9 swing from a vertical plane into a substantially horizontal plane, as shown in Fig. 6, wherein they are in alignment with the arm 12 which has swung away from the bracket 13. Upon reference to Fig. 6, it will be seen that by this construction the counter-balancing spring arrangement takes up very little space at the bottom of the cabinet when the bed is closed, thus permitting a very compact design.

A blanket retaining board is hingedly secured to the upper edge of the head or inner end of the mattress containing frame 5. The board is formed of upper and lower sections 14 and 15 which are connected together by hinges 16 at their abutting edges. In order to retain the upper section 14 in alignment with the lower section 15 when the bed is in the open position, as illustrated in Fig. 1, a vertical brace member 17 is attached to the front face of the upper section 14 and extends downwardly in front of the lower section 15. A second brace member 18 is carried upon the front face of the lower section 15 and is positioned in alignment with the upper brace member 17. It will thus be understood that the lower section 18 may swing rearwardly at an angle to the upper section, as shown in Fig. 6, but is restrained from swinging forwardly out of alignment with the upper section 17, as shown in Fig. 1. The lower blanket board section 15 carries a forwardly extending ledge 19 substantially at right angles thereto and pivotally connected by hinges 20 to the upper edge of the inner head end of the mattress containing frame 5.

To retain the blanket board sections 14 and 15 tightly against the bedding when the bed is in the closed position, as shown in Fig. 6, a swingable arm 21 is pivotally secured to the lower portion of the cabinet back 4 to extend forwardly and press against the back face of the blanket board section 14 when the bed is in the closed position, as shown in Fig. 6. The arm is resiliently held against the section 14 under the influence of an elongatable spiral spring 22 which is secured at its lower end to the back face of the blanket board section 15 and at its upper end to the arm 21 intermediately of its length.

When the bed is swung downwardly into the open position, as shown in Fig. 1, the blanket board moves upwardly and inwardly under the influence of the upward and inward swinging movement of the inner end of the mattress containing frame, and this movement causes the lower end of the spring 22 to approach and swing above the arm 21, whereby the tension upon the spring is released.

To prevent the blanket board sections 14 and 15 from following the mattress downwardly to the horizontal position when the bed is being opened, a length of cable 52 is attached at one end to the inner face of the blanket board section 14 and at the other end to a vertical eye bolt 23 which is carried upon a cross-member 24 forming a reinforcement for the cabinet back 4. The ends of the cross-member 24 are anchored to the side members 2 of the cabinet by corner brackets 25, whereby the cross-member is rigidly secured. As the eye-bolt 23 may be adjusted in height within the cross-member 24, the operating length of the cable 52 may be adjusted.

When the bed is being swung from the vertical closed position to the horizontal open position, the blanket board swings with and follows the mattress until the cable 52 is fully extended. The continued downward swinging movement of the bed, wherein the inner end of the mattress containing frame 5 swings upwardly and inwardly, causes the blanket board to be lifted upwardly and moved rearwardly into the position shown in Fig. 1. In order to accurately counter-balance the weight of the swinging bed, two or more springs 9 may be connected together in place of the single pair of springs 9 as shown, the additional springs may be either weaker or stronger depending upon the counter-balancing requirements.

The front edge of the cabinet top 3 is designed to carry a forwardly projecting ledge 26 and in the front recessed edge of which a tubular electric light 27 is contained. The outer end leg section 28 supporting the mattress frame 5 is designed to be positioned underneath the ledge 26 when the bed is in the closed position, as shown in Fig. 6. The ledge 26 is detachably secured to the cabinet top and the leg section 28 is detachably secured to the mattress frame, so that for the purpose of transportation the projecting ledge and leg section may be detached.

In the construction shown in Figs. 1 to 6, the piece of furniture 29 simulating a fireplace and mantel piece is normally positioned in front of the panel 7 when the bed is in the closed position. The piece of furniture is connected to one of the side members 2 of the cabinet by a hinge 30 and is supported upon a plurality of floor engaging castors 31, whereby the piece of furniture may be readily rolled from a position in front of the panel 7 to an outwardly swung position in order that the bed may be lowered. To compensate for any inequalities in the floor, the hinge 30 has its leaf 32 pivotally attached to the piece of furniture so that the piece of furniture is always supported by the castors 31 and not by the hinge. To open the bed the piece of furniture 29 is swung to one side and the panel 7 grasped by any suitably positioned handle on the face thereof and the bed swung downwardly from the position shown in Fig. 6 to the position shown in Fig. 1.

If it is desired to obtain privacy for an occupant of the bed, a cloth shield may be used to extend from the cabinet to the foot of the bed

on one side of the mattress containing frame 5. In the drawings I show such a cloth shield 33 of substantially triangular shape and attached at its upper corner to a spring 34 contained within the upper corner of the cabinet and at its forward corner attached to the foot of the mattress containing frame at one corner thereof. The shield is maintained against drooping by a rod 35 carried by the shield.

Figs. 7 and 8 illustrate an alternative arrangement, wherein a piece of furniture 36 simulating a fireplace is secured to the front of the panel 7. The fireplace includes a pair of side members 37 which flank the fireplace aperture 38 and are so arranged that their bottom edges 39 are spaced away from the floor upon which the structure rests in order to provide a clearance whereby such lower edges may swing downwardly and rearwardly into the cabinet when the bed is swung into the open position. To shield the clearance spaces underneath the bottom edges 39 of the side members 37, a pair of U-shaped base board members 40 rest upon the floor in front of and along the sides of the vertical and side planes of the front and side faces of the side members 37. The base board members 40 are fixed in place and the lower portions side members swing away therefrom when the bed is opened.

In Figs. 9 to 11 an arrangement is shown wherein a folding seat is positioned in front of and attached to the panel 7. The seat is so designed that when the mattress containing frame 5 and panel 7 is swung from the vertical closed position within the cabinet to the horizontal open position, the seat folds to be contained within the space underneath the horizontal panel.

In carrying out the foregoing arrangement a pair of forwardly extending arms 41 are secured to the front face of the panel 7 and are positioned substantially in alignment with the pins 6 about which the mattress containing frame swings. The seat 42 is supported upon an L-shaped frame 43 having its rear vertical end members 44 pivotally attached to the outer ends of the arms 41, whereby the arms constitute a support for the inner edge of the frame 43. A pair of swingable legs 45 are positioned underneath the front edge of the frame 42 and have their upper ends pivotally attached to the frame.

The lower ends of the legs are pivotally mounted upon brackets 46 carried upon a base and skirting member 47. A pair of arm rests 48 are mounted upon the frame 43 at the ends of the seat 42, and a seat back 49 is swingably mounted upon the pins 50 carried upon the rear portions of the inner faces of the arm rests 48 and is arranged to normally rest against the upper ends of the vertical members 44 when the seat is in the open position, as illustrated in Fig. 11.

When the bed is being opened the forwardly and downwardly swinging movement of the panel 7 causes the arms 41 to swing downwardly from the horizontal position shown in Fig. 10 into the vertical position shown in Fig. 11, whereby the seat supporting frame 43 moves downwardly and rearwardly about the rearwardly swinging movement of the legs 45, so that the seat folds into the position shown in Fig. 10. Before the panel 7 is swung downwardly the seat back 49 may be swung forwardly to rest upon the seat 42, or if this is not done the forward swinging movement of the panel 7 will cause the panel to contact the seat back and swing it forwardly and downwardly.

To assist the seat in its initial unfolding movement when the bed is being closed, a curved leaf spring 51 is secured at one end to the underneath portion of the frame 43 and adapted to resiliently press against the base 47 when the seat is folded. The spring assists in the upward movement of the frame 43 during the initial swinging movement of the panel 7 to close the bed.

From the foregoing description it will be apparent that I have devised a very simple and practical folding bed structure to which various articles of furniture may be attached, the structure being so arranged and designed that it may be placed in a relatively small room without giving the appearance of crowding; and, although I have shown and described a particular embodiment of my invention, it is to be understood that I may make any such changes or alterations that I may at any time deem necessary, without departing from the spirit of my invention as set forth in the appended claims.

What I claim as my invention is:

1. A folding bed structure of the character described comprising an open faced cabinet having a pair of stationary vertical side members, a mattress containing frame pivotally mounted intermediately of its length between the side members and swingable from a vertical position between the side members to a horizontal position extending outwardly from the side members and inwardly between the side members, a panel secured to the under face of the mattress containing frame and forming a closure for the open face of the cabinet when the mattress containing frame is in the vertical position, a downwardly extending mattress containing frame counter-balancing spring element anchored at its top to the inner end of the frame and at its lower end to the lower inner portion of the cabinet, a blanket board contained within the cabinet and formed of upper and lower sections hingedly connected together at their adjacent edges, the lower section being hingedly secured to the inner end of the mattress containing frame, the blanket board being movable from one substantially vertical position to another as the mattress containing frame is swung, a moveable spring actuated element supported by the cabinet and bearing against the back of the blanket board to urge it towards the open face of the cabinet and engaging the upper blanket board section when the mattress containing frame is in the vertical position and engaging the lower blanket board section when the mattress containing frame is in the horizontal position, and a blanket board retaining element forming a connection between the cabinet and the blanket board and under the restraint of which the movement of the blanket board is limited.

2. A folding bed structure as claimed in claim 1, wherein the blanket board is hingedly secured to the inner end of the mattress containing frame by a bedding supporting ledge extending forwardly from the lower edge of the lower blanket board section and is hingedly connected at its forward end to the inner end of the mattress containing frame.

3. A folding bed structure as claimed in claim 1, wherein a swingable arm is pivotally attached to the inner end of the mattress containing frame to extend in a substantially horizontal direction and to the free end of which the upper end of the counter-balancing spring element is attached, and an arm supporting bracket is posi-

tioned underneath the swingable arm to engage said arm and retain it in the horizontal position when the mattress containing frame is in the horizontal position.

4. A folding bed structure as claimed in claim 1, wherein the blanket board is hingedly secured to the inner end of the mattress containing frame by a bedding supporting ledge extending forwardly from the lower edge of the lower blanket board section and is hingedly connected at its forward end to the inner end of the mattress containing frame and wherein a swingable arm is pivotally attached to the inner end of the mattress containing frame to extend in a horizontal direction underneath the ledge extending forwardly from the lower edge of the lower blanket board section and to the free end of such arm the upper end of the counter-balancing spring element is attached, and an arm supporting bracket is positioned underneath the swingable arm to engage said arm and retain it in the horizontal position when the mattress containing frame is in the horizontal position.

5. A folding bed structure as claimed in claim 1, including a piece of furniture simulating a fireplace secured to the front of the panel which is secured to the mattress containing frame, a pair of fireplace side members flanking the fireplace aperture and swingable with the panel and having their bottoms spaced away from the floor upon which the structure rests, and a pair of base board members resting upon the floor in front of the vertical planes of the front faces of the fireplace side members and extending upwardly to substantially the same height as the bottoms of the side members.

6. A folding bed structure as claimed in claim 1, including an arm extending forwardly from the front of the panel which is secured to the mattress containing frame, a seat positioned in front of the panel when the panel is in the vertical position, an L-shaped seat supporting frame and upon the horizontal portion of which the seat rests and having its rear vertical portion pivotally attached to the outer end of the arm which constitutes a support for the rear edge of the L-shaped frame, and a swingable L-shaped frame supporting leg positioned underneath the forward portion of said frame and having its upper end pivotally attached to the frame and its

lower end pivotally mounted upon a base bracket resting upon the floor underneath the seat.

7. A folding bed structure of the character described comprising an open faced cabinet having a pair of stationary vertical side members, a mattress containing frame pivotally mounted intermediately of its length between the side members and swingable from a vertical position between the side members to a horizontal position extending outwardly from the side members and inwardly between the side members, a panel secured to the under face of the mattress containing frame and forming a closure for the open face of the cabinet when the mattress containing frame is in the vertical position, a downwardly extending mattress containing frame counter-balancing spring element anchored at its top to the inner end of the frame and at its lower end to the lower inner portion of the cabinet, an arm extending forwardly from the front of the panel, a seat positioned in front of the panel when the panel is in the vertical position, an L-shaped seat supporting frame comprising a horizontal portion upon which the seat rests and a vertical portion extending upwardly from the rear edge of the seat portion, the vertical portion being attached to the outer end of the arm which constitutes a support for the rear edge of the L-shaped frame, and a swingable frame supporting leg positioned underneath the forward portion of said frame and having its upper end pivotally attached to the frame and its lower end pivotally mounted upon a base bracket resting upon the floor underneath the seat.
